(57) **CLAIM**

The ornamental design for an aerosol generating device, as
shown and described.

DESCRIPTION

FIG. 1 is a front, top, and right side perspective view of an
aerosol generating device showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof.

FIG. 7 is a right side elevational view thereof; and,
FIG. 8 is another front, top, and right side perspective view
thereof shown in a position of use.

The evenly spaced broken lines depict portions of the
aerosol generating device that form no part of the claimed
design. The dot-dash broken lines form a boundary between
the claimed and unclaimed portions of the aerosol gener-
ating device, the dot-dash broken lines forming no part of the
claimed design.

The greyscale shadings show contours and neither ornamen-
tation nor coloration nor surface finishing.
